UNITED STATES PATENT OFFICE.

HENRY L. HOFFMANN, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed April 3, 1920. Serial No. 371,049.

To all whom it may concern:

Be it known that I, HENRY L. HOFFMANN, a citizen of the United States, residing at New York, in the county of New York and 5 State of New York, have invented certain new and useful Improvements in Telephone-Exchange Systems, of which the following is a full, clear, concise, and exact description.

10 This invention relates to telephone exchange systems and particularly to systems comprising a toll exchange and an automatic telephone exchange.

An object of the invention is to provide 15 improved and simplified circuit arrangements for use in the extension of connections from a toll exchange to subscribers of an automatic telephone exchange, involving a repeater, comprising means for repeating 20 voice currents and means for repeating impulses, to be used in connection with an incoming selector at the automatic exchange, said means for repeating voice currents being normally disconnected from the trunk 25 line and connected thereto when the last switch of the train of switches to be operated, is set.

In systems of this type it is necessary to 30 maintain the voice current repeating means disconnected from the outgoing conductors over which the impulses are transmitted to said switches, during the time such impulses are being transmitted.

The invention consists in the provision 35 of a circuit arrangement wherein the relay, which switches in the repeater, is included in the test and release wire without interfering with the testing and releasing operations, the arrangement being such that, when 40 the final switch is set on the called line, a circuit change is produced, which causes the switching relay to operate.

Other new and useful features will be set 45 forth in the following description and the accompanying drawings in which Figs. 1 and 2 illustrate diagrammatically, the means which may be employed by an operator at a toll exchange in calling a subscriber of an 50 automatic exchange. The two exchanges are connected by trunk lines, one of which is shown terminating at one end in the repeater C and the other end in a jack 6 at the toll exchange.

Referring to Fig. 1 of the drawings, that portion of the circuit to the left of the dotted 55 portion of the trunk is located at the toll exchange and that to the right thereof, at the automatic exchange. A portion only of the cord circuit, at the toll operator's position has been shown, since such circuits are 60 well known. It will be understood that long distance calls for subscribers at the automatic exchange will arrive at the toll operator's position and such calls may be extended through the medium of cord circuit A and 65 over the trunk line to the automatic exchange. The repeater C comprises a repeating coil 17 for repeating voice currents over the trunk line to the automatic exchange, and a relay 8 for repeating impulses, transmitted by an impulse sender S at the operator's position, directly to the stepping magnets of the switches.

The repeater C is located at the automatic 70 exchange and is associated with an incoming or first selector such as D shown in Fig. 2. At F, a connector switch is shown. The station of a subscriber B is shown whose line terminates in the contact bank of the switch F. At E, a second selector switch is 75 schematically shown. There may be a number of switches such as E, wired and equipped the same as switch D shown on Fig. 2, interposed between the first selector and the connector switches. The sets of impulses for setting the various switches of the train are successively conveyed directly to the operating magnets of the switches, 80 from the impulse relay S.

The invention will be more readily understood from a detailed description of the 85 operation.

Assuming that the operator at the toll exchange desires to establish a connection with the subscriber B at the automatic 90 exchange, the calling plug of cord circuit A may be inserted into jack 6 of the trunk circuit extending to the repeater C at the automatic exchange, whereupon relay 8 is operated over a circuit extending from ground, 95 through resistance 30, left-hand winding of relay 8, outer normal contacts of relay 12, conductor 40, tips of jack 6 and plug 5, upper normal contacts of ringing key 7 and dialing key 10, windings of relays 4 and 3, 100 lower normal contacts of dialing key 10 and 105

ringing key 7, rings of plug 5 and jack 6, conductor 41, inner normal contacts of relay 12, right-hand winding of relay 8, and resistance 31 to grounded battery. Relay 8 in attracting its armature completes circuits for the energization of slow-to-release relay 9 of the trunk circuit C and slow-to-release relay 108 of the selector, said circuits extending from ground, through the armature and front contact of relay 8 and thence in parallel to battery, one path extending through the winding of relay 9, and the other through the upper normal contacts of relay 25, conductor 101, inner left-hand normal contacts of relay 109 and winding of relay 108.

The operator may now actuate dialing key 10, thus replacing the loop for relay 8, through relays 3 and 4, by a loop through the contacts 42 of sender S, and proceed to send impulses to select the desired line B. The sender schematically shown at S is, for the purpose of convenience, represented as the well known dial or rotary type although it is to be understood that it may be of any well known type adapted to cause a plurality of series of interruptions in a line circuit.

With each interruption of the contacts 42 of the sender S, relay 8 will retract its armature thereby completing a circuit from grounded battery, through the winding of primary magnet 111, winding of relay 110, front contact and left-hand armature of relay 108, outer left-hand normal contacts of relay 109, conductor 102, lower normal contacts of relay 25, and back contact and armature of relay 8 to ground. Magnet 111 in response to these impulses operates to step the selector switch brushes 116, 117 and 118 from group to group of the trunk lines terminating at said switch.

The relay 110 is energized in series with magnet 111, and being of the slow-to-release type does not retract its armature during the sending of a series of impulses. In attracting its armature relay 110 completes a circuit for relay 113 which then locks over a circuit extending from grounded battery, through the winding of relay 113, front contact and armature of relay 113, vertical off-normal contacts 151, which are closed in the first vertical step of the brushes, right-hand contacts of secondary magnet 112, and right-hand alternate contacts of relay 108 to ground. Relay 108 being of the slow-to-release type does not retract its armatures during the sending of a series of impulses. At this point it should be noted that the left-hand winding of relay 14, which eventually operates over the release conductor 103, is shunted by the direct path to ground at the contacts of relay 108, for the battery at the winding of relay 113.

At the termination of the series of impulses, the circuit of relay 8 is maintained

closed for an appreciable time so that relay 110 and magnet 111 deenergize. The switch stops at the selected group of contacts and as relay 110 retracts its armature due to the prolonged interruption of its circuit, a circuit for secondary magnet 112 is completed said circuit extending from grounded battery, through the left-hand contacts of magnet 112, normal contacts of relay 110, alternate contacts of relay 113, contacts 151, right-hand normal contact of magnet 112, and right-hand alternate contacts of relay 108 to ground. Upon energizing, magnet 112 operates to rotate the brushes 116, 117 and 118 one step into engagement with the first set of contacts of the selected group. Near the end of its stroke, magnet 112 opens its interrupter contacts, thereby breaking the locking circuit of relay 113. The interrupter contacts are not opened however until the test brush has reached the first contact. Upon de-energizing, relay 113 opens the energizing circuit of magnet 112. Magnet 112 retracts its armatures to again close its interrupter contacts. The operation now depends upon whether or not the first trunk line, the terminals of which are now engaged by the selector brushes, is busy or not. If this trunk line is busy, ground potential will be present upon the test terminal with which test brush 118, is in engagement, and this ground will serve to maintain relay 113 energized and to again energize magnet 112. Magnet 112 in energizing moves the brushes 116, 117 and 118 into engagement with the next set of contacts. It will be seen that as long as brush 118 engages grounded or busy contacts, relay 113 will remain energized and the stepping magnet 108 will advance the brushes of the selector D step-by-step. When an idle or non-grounded test contact is reached, assumed to be the test contact 121, and magnet 112 retracts its armature, relay 113 will retract its armature, thereby completing a circuit for the relay 109, said circuit extending from grounded battery, winding of relay 109, normal contacts of relay 113, off-normal contacts 151, right-hand contacts of magnet 112, right-hand alternate contacts of relay 108 to ground. It will be noted that relay 14 does not energize at this time due to the shunt to ground at relay 108 for the battery at the winding of relay 109.

Upon energization of relay 109, a circuit will be completed for slow-to-release relay 128 of the connector switch F, said circuit extending from grounded battery, through the winding of relay 128, inner left-hand normal contacts of relay 136, terminal 125, bush 122, terminal 119, brush 116, inner left-hand alternate contacts of relay 109, conductor 101, upper normal contacts of relay 25, and thence in parallel with slow-to-

release relay 9 of trunk circuit C to the front contact and armature of relay 8 to ground.

5 Relay 128 in energizing connects ground through its right-hand alternate contacts to the test terminal 127 to render the connector busy and to maintain relay 109 energized and at its left-hand contacts prepares the impulse circuit for the primary stepping 10 magnet 131.

15 The operator may now operate the impulse sender S to send out the next or tens series of impulses. Each opening of the contacts 42 of the sender will cause the retraction of the armature of relay 8 as before. With the first retraction of the armature of relay 8, a circuit for slow relay 129 and stepping magnet 131 will be completed, said circuit extending from ground, through the 20 armature and back contact of relay 8, lower normal contacts of relay 25, conductor 102, left-hand alternate contacts of relay 109, brush 117, terminal 120, brush 123, terminal 126, outer left-hand normal contacts or relay 25 136, left-hand contacts of relay 128, contacts 160, winding of slow-to-release relay 129 and winding of magnet 131 to battery. Magnet 131 will be energized and will move the connector brushes 143, 144, and 145 one step. 30 At the first step of the switch off-normal contacts 160 will be opened and contacts 161 and 162 will be closed. Relay 129 is also energized and being of the slow-to-release type holds its armature attracted 35 throughout the remaining impulses of the tens series which pass through contacts 162 and the alternate contacts of relay 129. In accordance with the remaining impulses of the tens series, magnet 131 is repeatedly 40 energized and deenergized and steps the connector switch brushes 143, 144 and 145 from group to group of the subscriber's line contacts terminating therein until the tens group, in which the wanted line terminates, 45 is reached. The circuit for relay 8 will then be maintained closed thus holding open the circuit for relay 129 and magnet 131. Relay 129 then retracts its armature thus disconnecting slow-to-release relay 129 and 50 magnet 131 from the impulse circuit and connecting slow-to-release relay 132 and secondary magnet 133 thereto.

55 The operator now sets the impulse sender to send the final or units series of impulses. With the first retraction of the armature of relay 8, a circuit is closed through slow-to-release relay 132 and secondary magnet 133 similar to that over which relay 129 and magnet 131 were energized when the tens 60 series of impulses were sent. Magnet 133 and relay 132 are both energized; the former moves the brushes one step and the latter completes a circuit at its front contact and inner armature for relay 134. Relay 134 65 then locks up over a circuit extending from

grounded battery, through the winding, front contact and right-hand armature of relay 134, and front contact and right-hand armature of relay 128 to ground. Relay 14 of trunk circuit C is not operated due to 70 the shunt to ground at the contacts of relay 128 for the battery at the winding of relay 134.

In accordance with the remaining impulses sent by the sender S, magnet 133 is 75 repeatedly energized and deenergized, moving the brushes from set to set of the line terminal contacts of the selected tens group.

80 When the connector switch brushes are positioned on the terminals of the called line, the circuit of relay 8 will remain closed, causing it to hold up its armature thus holding open the circuit for relay 132 and magnet 133. Relay 132 being of the slow-to-release type does not retract its armatures until the sending of the series of impulses ceases. 85

90 Assuming that the called line is idle, in which case battery will be present upon the test terminal 148 of the called line, a circuit will be completed for relay 135, said circuit extending from battery at terminal 148, brush 145, left-hand winding of relay 135, left-hand contacts of relay 134, back contact and outer armature of relay 132, front 95 contact and right-hand armature of relay 134 and front contact and right-hand armature of relay 128 to ground. Relay 135 thereupon attracts its armatures and completes a locking circuit for itself, said circuit extending from grounded battery, through the right-hand winding and inner right-hand armature and front contact of relay 135, and front contact and right-hand armature of relay 128 to ground. A circuit is also completed for relay 136, said circuit 100 extending from grounded battery, through the winding of relay 136, back contact and inner armature of relay 132, front contact and right-hand armature of relay 134, and front contact and right-hand armature of relay 128 to ground. 105

105 Relay 136 in attracting its armatures extends the calling station to the conductors of the called station, and opens 110 the circuit for slow-to-release relay 128. Relay 128 in deenergizing, removes the shunt at its right-hand contacts for relay 14 and current through the windings of relay 136, 134 and 135 in parallel flows 115 over the release conductor 103 through the left-hand winding of relay 14 to ground at the left-hand contacts of relay 9 of trunk circuit C. Relays 136, 134 and 135 are thus maintained energized and relay 14 is energized over this circuit. Relay 14, in operating, at its right-hand armature, completes a locking circuit for itself and a circuit for the energization of relay 25, and at its left-hand alternate contacts short circuits its 120 125 130

left-hand winding. Relay 25 in energizing, connects battery and ground through repeating coil 17 to the trunk conductors 101 and 102 now extended through to the called subscriber station B, and closes the primary side of the repeating coil.

The operator may now restore dialing key 10 to normal and then actuate listening key 11 to ascertain if the called line is busy. Since the called station is idle, no busy tone will be heard. The operator may then actuate ringing key 7, thereby completing a circuit for ringing current responsive relay 18, said circuit extending from ground, through the upper alternate contacts of key 7, tips of jack 5 and plug 6, conductor 40, upper left-hand winding of repeating coil 17, winding of relay 18, condenser 19, lower-most alternate contacts of relay 25, lower left-hand winding of repeating coil 17, conductor 41, rings of jack 6 and plug 5 and lower alternate contacts of key 7 to source of alternating current 1. Relay 18 thereupon energizes and completes a circuit for relay 16, said circuit extending from ground, through the contacts of relay 18, winding of relay 16, and left-hand winding of relay 12 to grounded battery. Relays 16 and 12 are thereby energized, the former serving to project ringing current from the source 50 over the talking conductors 102 and 101 to the called substation, and the latter serving to disconnect battery and ground from the conductors 40 and 41 of the trunk circuit C, thereby maintaining relay 8 energized through the alternate contacts of relay 12. Restoration of key 7 to normal releases relays 18, 16 and 12.

Upon the response of the called subscriber, relay 15 of trunk circuit C is energized over a circuit extending from grounded battery, winding of relay 15, resistance 21, lower right-hand winding of repeating coil 17, lower normal contacts of relay 16, lower alternate contacts of relay 25, and thence over conductor 102 through to the substation loop and back to conductor 101, through the upper alternate contacts of relay 25, upper normal contacts of relay 16, upper right-hand winding of repeating coil 17, and resistance 20 to ground. Relay 15 in energizing, completes a circuit at its contacts for relay 12 which in energizing again removes battery and ground from conductors 40 and 41, thus deenergizing relay 3, and it in turn extinguishing lamp 2, thus indicating to the operator that the called station B has answered.

Station B is now connected for conversation, talking battery for said station being supplied through resistances 20 and 21, and the right-hand windings of repeating coil 17.

During the time that the called subscriber has the receiver removed from the switch-

hook, the operator may change cords without releasing the connection since relay 12 will be energized thus maintaining relay 8 operated.

Upon completion of conversation and restoration of the receiver to the switchhook at station B, relay 15 deenergizes and in turn relay 12. The latter in deenergizing connects battery and ground through relay 8 to and the normal contacts of relay 12 to relay 3 of the cord circuit A. Relay 3 thereupon energizes, thus lighting lamp 2 and indicating to the operator that the subscriber of station B has restored the receiver to the switchhook.

The operator may then remove plug 5 from jack 6, thereby opening the circuit for relay 8. Relay 8 then retracts its armature thus opening the circuit for slow-to-release relay 9. Relay 9, in deenergizing, releases relays 14 and 25 and removes ground from release conductor 103 thereby releasing relay 109 of selector D and relays 136, 135 and 134 of connector F. Relay 109, in releasing, completes a circuit for release magnet 115 over a path extending from grounded battery, through the winding of magnet 115, off-normal contacts 150, right-hand armature and back contact of relay 109, and front contact and armature of relay 108 to ground. Upon actuation, magnet 115 restores the selector switch to normal in the well known manner. Relay 136 of connector F, in releasing, completes a circuit for release magnet 130 over a path extending from grounded battery, through the winding of magnet 130, off-normal contacts 161, right-hand armature and back contacts of relay 136, and back contact and right-hand armature of relay 128 to ground. Upon actuation, magnet 130 restores the connector switch F to normal.

Assuming that the wanted line is busy, in which case the test contact 148 will have a ground potential thereon, relay 135 will not operate. Relay 136 will energize however as soon as relay 132 releases, and relay 134 will be maintained energized over paths heretofore described in the case of a successful call.

As soon as relay 136 energizes, current will flow over the release conductor through the winding of relay 14 to energize relay 14 as before; relay 14 in energizing, locks up and completes a circuit for relay 25, thereby rendering the trunk circuit continuous.

A busy tone will then be transmitted over a path extending from ground, through the secondary winding 141 of the busy signal device, condenser 140, outer left-hand normal contacts of relay 135, inner left-hand alternate contacts of relay 136, terminal 125, brush 122, terminal 119, brush 116, inner left-hand alternate contacts of relay 109, conductor 101, upper alternate contacts of 130

relay 25, upper normal contacts of relay 16, upper left-hand winding of repeating coil 17, and resistance 20 to ground. This tone in the secondary of repeating coil 17 is introduced into the primary. The operator after having operated sender S may restore dialing key to normal and actuate key 11 to connect her set (not shown) to the cord circuit whereupon she will hear the busy tone indicating to her that the called line is busy.

The operator may then withdraw plug 5 from jack 6 whereupon all relays of trunk circuit C are released and relay 109 of selector switch C and relays 136 and 134 of connector switch F are released as heretofore described. The release magnets of selector switch D and connector switch F are thereupon actuated and restore their respective switches to normal.

What is claimed is:

1. In a telephone exchange system, an operator's position, a sender, an automatic telephone exchange called subscriber's line circuit, a connecting circuit including a trunk line, a repeater, and a train of automatic switches for establishing a connection between said position and said line circuit, said repeater being provided with a repeating coil normally disconnected from said connecting circuit for repeating voice currents and also with means for repeating impulses from said sender to operate said switches, electromagnetic switching means adapted upon energization to connect said repeating coil to said connecting circuit, and means for operating said switching means as soon as connection is established with the called line circuit.
2. In a telephone exchange system, an operator's position, an automatic telephone exchange called subscriber's line circuit, senders therefor, a connecting circuit including a trunk line, a repeater, and a train of automatic switches for establishing a connection between said position and said line circuit, said repeater being provided with a repeating coil normally disconnected from said connecting circuit for repeating voice currents and also with means for repeating impulses from said sender at said operator's position to operate said switches, relays adapted upon energization to connect said repeating coil to said connecting circuit and means for operating said relays as soon as connection is established with the called line circuit.
3. In a telephone exchange system, a calling station, a called station, senders therefor, a connecting circuit including automatic switches, a repeating relay in said circuit operated by said sender at said calling station to set said switches, a repeating coil in said connecting circuit having a source of talking battery connected thereto, said repeating coil being normally disconnected from the called end of the connecting circuit, and means for connecting said repeating coil in circuit with the called station as soon as the last series of impulses has been transmitted.
4. In a telephone exchange system, a calling station, a called station, means including a repeater and a train of automatic switches for interconnecting said stations, a relay associated with the first switch of the train, means for preventing the operation of said relay including a circuit at each succeeding switch, and means for operating said relay as soon as the last switch of the train is set.
5. In a telephone exchange system, a calling station, a called station, senders therefor, a connecting circuit including a train of automatic switches, a repeating relay in said circuit operated by the sender of said calling station to set said switches, a repeating coil between said relay and said switches, having a source of talking battery connected thereto, said repeating coil being normally disconnected from the called end of the connecting circuit, relays associated with said connecting circuit adapted upon energization to connect said repeating coil to the called end of the connecting circuit; and means for energizing said relays as soon as the last series of impulses has been transmitted.
6. In a telephone exchange system, a manual exchange, an automatic exchange, a two conductor trunk circuit extending between said exchanges, means including a repeater and a train of automatic switches for establishing a connection between an operator's position at said manual exchange and a subscriber's line terminating at said automatic exchange, a pair of talking conductors and a third conductor for each of said automatic switches, electromagnetic switching means associated with the first switch of said train, a circuit for said switching means successively extended over said third conductor through said train of switches, and means for operating said switching means over said circuit as soon as the last switch of the train is set.
7. In a telephone exchange system, an operator's position, a called station, means for connecting said operator's position with said called station including a train of automatic switches, a pair of talking conductors and a release conductor for each of said switches, a source of talking battery at the first switch of said train, a relay associated with the first switch of the train adapted upon energization to connect said source of talking current to the talking conductors of said switches, a second relay associated with the first switch of the train adapted upon energization to energize said

first mentioned relay, means for preventing the operation of said second relay, including a circuit at each succeeding switch, during the setting of said switches and means for energizing said second relay as soon as the last switch of the train is set on the called line.

8. In a telephone exchange system, an operator's position, a called station, means including a trunk circuit and a train of automatic switches for establishing a connection between said position and said called station, a relay associated with said trunk circuit, means associated with each switch of the train for preventing the operation of said relay during the establishment of the connection, and means for operating said relay as soon as the terminals of the called line have been reached.

9. In a telephone exchange system, a calling and called station, means including a train of switches for interconnecting said stations, a pair of talking conductors and a third conductor for each of said switches, a relay associated with the first switch of said train, adapted to be operated over said third conductor, means at each of said switches for preventing the operation of said relay over said third conductor until the last switch of said train has been set and means for operating said relay as soon as the last switch of the train is set upon the terminals of the called station.

10. In a telephone system, a series of automatic switches including talking conductors and a test conductor, a repeater at the first of said switches comprising means for repeating impulses to succeeding switches and for repeating voice currents, said voice current repeating means being normally disconnected from the talking conductors, means for operating said impulse repeating means to transmit impulses over said talking conductors beyond said repeater, to set said switches and a relay included in said test conductor at said first switch and operating when the last set of impulses is transmitted to connect said voice current repeater to the talking conductors.

11. In a telephone system, a series of automatic switches including talking conductors and a test conductor, a repeater at the first of said switches comprising means for repeating impulses to succeeding switches and for repeating voice currents, said voice current repeater being normally disconnected from the talking conductors, means for operating said impulse repeating means to transmit impulses over said talking conductor beyond said repeater to set said switches, a relay included in said test conductor at said first switch shunted while the connection is progressing from switch to switch, and means for opening said shunt when the last switch is set to

connect said voice current repeater in said talking conductors.

12. In a telephone exchange system, a calling station, an automatic switch, an impulse sender at said calling station for setting said switch, a repeating coil between said sender and said switch conductively separating said calling station and said switch, and means for automatically connecting said coil in circuit with said calling station and said switch as soon as said switch has been set.

13. In a telephone exchange system, an operator's cord circuit, an automatic switch, an impulse sender associated with said cord circuit for setting said switch, a repeating coil between said sender and said switch conductively separating said cord circuit and said switch, and means for automatically connecting said coil in circuit with said cord circuit and said switch as soon as said switch has been set.

14. In a telephone exchange system, an operator's cord circuit, an automatic switch, a called station, an impulse sender associated with said cord circuit for setting said switch on the terminals of said called station, a repeating coil between said cord circuit and said switch, means for connecting said coil in circuit with said cord circuit and said called station as soon as the terminals of the called station are reached, means for informing the operator of the busy condition of the line of the called station, and operator controlled means for ringing the called station if the line of the called station is idle.

15. In a telephone exchange system, a calling station, a train of switches, a dial for setting said switches, sources of direct current associated with the first switch of the train, a repeating coil between said dial and said train of switches conductively separating said sources of direct current, and means for automatically connecting said coil in circuit with said switches as soon as the last switch of the train has been set.

16. In a telephone exchange system, a calling station, a called station, a trunk circuit, means including a train of switches and said trunk circuit for interconnecting said stations, a repeating coil in said trunk circuit, a by-pass around said repeating coil over which said switches are set by said calling station, and means for connecting said repeating coil in circuit with said calling and called stations as soon as the last switch of the train is set.

17. In a telephone exchange system, a first office, a cord circuit thereat, a second office, a trunk circuit extending between said offices, a repeating coil, a train of switches and a called station at said second office, an impulse sender for the cord circuit, a by-pass around said repeating coil for control-

ling said switches, and means operative as soon as the last switch of the train is set to open said by-pass and to connect said repeating coil in circuit with said cord circuit and 5 said called station.

18. In a telephone exchange system, a first exchange, a second exchange, a trunk circuit extending between said exchanges, an operator's position at the first exchange, a 10 called station at the second exchange, a train of switches at the second exchange, means including an impulse sender at the first exchange for setting said switches over said trunk circuit, sources of talking and signaling current at the second exchange associated with said trunk circuit, a repeating coil in said trunk circuit conductively separating said sources of current and having its primary and secondary windings normally 15 disconnected from the ends of the trunk circuit, and means operating as soon as the 20 last switch of the train is set for connecting

both windings of the coil in the trunk circuit.

19. In a telephone system, subscribers' 25 lines, an operator's position, a supervisory signal thereat, a trunk circuit terminating at one end before said operator's position, an automatic switch at the other end of said trunk circuit, means at the operator's position for connecting with said trunk circuit, means for sending impulses over said trunk circuit, means responsive thereto for operating said switch to extend said trunk to a called line, said trunk being open at both 30 ends during the transmission of impulses, and means operative as soon as said switch has been set for closing both ends of said trunk to place said supervisory signal under the control of the called subscriber. 35

In witness whereof, I hereunto subscribe my name this 31st day of March A. D., 1920. 40

HENRY L. HOFFMANN.
